ROBERT H. LAWSON, OF PAWTUCKET, AND AUGUSTIN GAGNÉ, OF CENTRAL FALLS,
RHODE ISLAND, ASSIGNORS TO HEMPHILL COMPANY, OF CENTRAL FALLS, RHODE
ISLAND, A CORPORATION OF MASSACHUSETTS

KNITTING MACHINE OPERATING MECHANISM

Application filed January 8, 1929. Serial No. 331,098.

This invention relates to knitting machine operating mechanism.

In order that the principle of the invention may be readily understood, we have disclosed one embodiment of means for practising the same in the accompanying drawings, where-in—

Fig. 1 is a rear elevation of a portion of the operating mechanism of a circular knitting machine;

Fig. 2 is a side elevation viewed from the right of Fig. 1 with one of the side frames of the machine removed;

Fig. 3 is a vertical section on the line 3—3 15 of Fig. 2; and

Fig. 4 is a plan view of the mechanism shown in the other figures.

While this invention is not restricted to circular knitting machines of the Banner type, 20 it is particularly applicable thereto in that it involves novel means for supporting and operating the so-called "104" gear of the Banner machine of the general type shown in the patent to Joshua D. Hemphill, No. 933,443, and 25 many subsequent patents.

Heretofore the 104 gear has been mounted upon a stud extending through one of the frames only of the machine, and it has been impossible, with the prior construction, to 30 support the same upon a shaft with two bearings because the 104 gear has heretofore been provided upon one face with a pin to which a connecting rod is suitably connected. The proper movements of such connecting rod 35 would have been impossible if a shaft had been provided for the 104 gear. According to the present invention the said pin and connecting rod are replaced by an eccentric and its connecting rod, as hereinafter disclosed, and the 104 gear is mounted upon a horizontal shaft supported in two uprights of the framing. Attention is called to the patent to Lawson & Lawson, No. 1,702,608, dated February 19, 1929, wherein the gear 45 is identified as the "104" gear. This gear is a characteristic element of the Banner knitting machine, and the present invention is directed to improved means for supporting and operating the same.

Referring more particularly to the draw-

ings, we have, in Figs. 1, 3 and 4, represented the two uprights of the framing at 1, 2, and we have therein provided openings 3 and 4 in connection with which we provide suitable bearings indicated generally at 5 and 6. Said 55 bearings themselves may be of any suitable character or type, and it is unnecessary to describe the same in detail.

The bearing shown at 5 is or may be the bearing heretofore provided for the stud that supported the 104 gear, but the bearing indicated at 6 is a new bearing in that heretofore the second bearing has never been supplied for the 104 gear. The shaft whereon the 104 gear is received is indicated at 7, and the 104 gear itself is indicated at 8. The said shaft is novel in this organization, and is represented as broken away at its two ends, which ends, or either of them, may receive cams or driving means. Formerly the 104 gear was 70 loosely mounted upon the stud. While in the present construction the 104 gear 8 may be loosely mounted upon the stud 7, we have represented it as keyed thereon as at 9, so that if driving means be provided for the shaft, 75 the 104 gear will be positively driven. Said 10 104 gear is provided with an eccentric 10 of any suitable construction operatively associated with which is the connecting rod 11 therefor. A suitable cover 12 is also provided. 80

In Figs. 1, 3 and 4, the usual clutch member 13 is provided adapted to mesh as usual with the clutch members 14 and 15 which need not be fully described further than to state that the clutch member 15 has integral or formed therewith the pinion 16 which is reciprocated by the quadrant 17. The said quadrant is pivotally mounted as usual at 18 and to the arm 19 thereof the connecting rod is pivotally connected at 20 by means of a 85 stud 21 having thereon a collar 22, as indicated clearly in Fig. 3. The clutch member 14 has fast therewith the pinion 23 by which the 104 gear is itself driven from the usual source. By the foregoing construction the 90 104 gear is more satisfactorily supported and without strain than in the former construction.

Having thus described one illustrative embodiment of the invention, it is to be under- 100

stood that although specific terms are employed, they are used in a generic and descriptive sense and not for purposes of limitation, the scope of the invention being set forth in
5 the following claims.

We claim:

1. In a circular knitting machine of the so-called Banner type, the 104 gear, a shaft for supporting the same, spaced upright members
10 of the framing at opposite sides of said 104 gear, bearings for said shaft mounted in the said members of the framing of the machine, an eccentric fast with said 104 gear between said framing members, a connecting
15 rod for said eccentric, the quadrant and pivotal operating connections between said connecting rod and said quadrant.
2. In a circular knitting machine of the so-called Banner type, the 104 gear, a shaft for supporting the same, spaced upright members
20 of the framing at opposite sides of said 104 gear, two bearings for said shaft supported upon the said members of the framing of the machine, an eccentric between said
25 framing members upon said 104 gear and surrounding said shaft, a connecting rod extending from said eccentric, the quadrant for reciprocating the needle cylinder or recipro-
30 cable element, and pivotal operating connections between said connecting rod and said quadrant.
3. A circular knitting machine of the so-called Banner type having a quadrant, a shaft whereon the same is mounted, a connecting
35 rod pivotally connected to said quadrant, the "104" gear, an eccentric fast with said "104" gear and adapted to operate said connecting rod, a shaft supporting said "104" gear, two bearings for said shaft at opposite sides re-
40 spectively of said "104" gear, and two spaced upright members of the framing to which said bearings are respectively secured.

In testimony whereof, we have signed our names to this specification.

45

ROBERT H. LAWSON.
AUGUSTIN GAGNÉ.
